UNITED STATES PATENT OFFICE

ARTHUR JOSEPH COURTOIS, OF MONTAGUE CITY, MASSACHUSETTS, ASSIGNOR OF ONE-FOURTH TO JAN P. CLARY, OF HARTFORD, CONNECTICUT

COMPRESSOR APPARATUS

Application filed May 25, 1931. Serial No. 539,925.

This invention relates to certain new and useful improvements in compressors and re-compressor apparatus.

The primary object of the invention is to provide an air compressor embodying reciprocating pistons, together and working in communicating cylinders with a rotary motor having a drive connection with the pistons in which rotary is transformed into rectilinear motion, the apparatus working to draw air thereinto at atmospheric pressure to be passed through stages of compression and re-compression for delivery to a storage tank.

A further object of the invention is to provide an air compressor embodying a plurality of aligned cylinders with connected pistons reciprocating in two cylinders and spaced by an intermediate cylinder with valve devices forming communication between the several cylinders and a rotary drive having gear connections with the connecting shaft of the pistons and cam devices for effecting reverse reciprocation of the piston connecting shaft for the purpose of drawing air into one end cylinder at atmospheric pressure which is transferred to the intermediate cylinder and initially compressed therein and forced therefrom into the third cylinder for final compression and delivery to a storage tank.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a top plan view of an air compressor constructed in accordance with the present invention;

Figure 2 is an enlarged fragmentary top plan view, partly broken away and shown in section and illustrating and driving and reversing mechanism for the piston devices;

Figure 3 is a vertical longitudinal sectional view taken on line 3-3 of Figure 1, illustrating three aligned cylinders of the apparatus, a piston in each end cylinder connected

by a rod and the valve devices forming communication with the several cylinders;

Figure 4 is a cross-sectional view taken on line 4-4 of Figure 3; and

Figure 5 is a cross-sectional view taken on line 5-5 of Figure 1.

The air compressor comprises a base 10 to facilitate mounting of the apparatus upon a support of any character, the base frame carrying intermediate cylinder 11 constituting an air storage chamber, an end cylinder 12 to receive air at atmospheric pressure and an opposite end cylinder 13 constituting a re-compressor cylinder. The intermediate cylinder 11 is open at its upper end and is closed by a flat cover wall 14 for the support of operating mechanism associated with pistons in the cylinders 12 and 13.

As shown in Figure 3, the outer end of the cylinder 12 is closed by an end wall 14 having a centrally disposed inwardly opening check valve 15 set therein that is tensioned as at 16 and said end wall 14 carries an air filter screen 17 overlying the air intake check valve 15 which may assume any form desired.

A reciprocating piston 18 working in the cylinder 12 separates the two cylinders 11 and 12, communication between these two cylinders being established by the spring pressed check valve 19 carried by the piston 18 and opening in a direction toward the cylinder 11. The cylinders 11 and 13 are separated by a partition 20 and said partition carries a tensioned check valve 21 opening in a direction toward the cylinder 13. The cylinder 13 has a portion of the inner end thereof as at 22 spaced from the partition 20 forming communication between the interior of the cylinder 13 and a longitudinally extending by path 23 communicating with a chamber 24 in a housing carried by the end wall 25 at the outer end of the cylinder 13 and said end wall 25 within the chamber 24 carries a tensioned check valve 26 opening from the chamber 24 in a direction toward the cylinder 13. A piston 27 reciprocates in the cylinder 13 and a piston rod 28 extending through a central bearing 29 in the partition 20 connects the two pistons 18 and 27 and said piston rod 28 has a threaded portion 30 of a length substan-

tially corresponding to the length of the cylinder 11 and with which driving devices are associated for effecting reciprocating movements of the pistons 18 and 27.

- 5 As shown in Figure 4, a vertical shaft 31 is journalled at its upper end in the cover wall 14 of the cylinder 11 and its lower end journalled in a cage 32 supported upon the inner wall of the cylinder 11 and said cage, as 10 shown in Figure 3 has a worm wheel 33 journalled therein and through which the threaded portion 30 of the piston rod for the two pistons extends, the lower end of the shaft 31 carrying a worm 34 engaged with the worm 15 wheel 33. A bevel gear 35 is fixed to the upper end of the shaft 31 above the cover wall 14 and with which driving devices are associated. An electric motor 36 supported upon the cover wall 14 has its shaft 37 supported 20 in suitable bearings and extends over the bevel gear 35 and said shaft 37 carries a pair of spaced bevel pinions 38 having clutch faces 39, the pinions 38 being engaged with diametrically opposite sides of the gear 35 and 25 being loose on said motor shaft. A shifter-shaft 40 is reciprocable in bearings 41 rising from the cover wall 14 and arranged parallel to the motor shaft 37 and said shaft 40 has a laterally directed arm 42 fixed thereto that 30 carries a double clutch element 43 engageable with the clutch members 39 upon the pinions 38. Reciprocating means for the shifter-shaft 40 to effect shifting movement of the clutch member 43 includes a worm 44 upon the 35 motor shaft 37 that engages with the worm wheel 45 that carries an eccentric pin 46 that extends within a rectangular frame 47 fixed to the shaft 40 and engageable with the sides of the frame to effect shifting movement of 40 the shaft 40. To retain the double clutch member 43 in positive engagement with either of the clutch members 39, a spring device is associated with the shaft 40 and includes a lever 48 pivotally mounted as at 49 and having 45 one end pivotally connected as at 49a to a link 50a attached to a tensioned plunger in the cylinder 50, the other end of the lever 48 carrying a slotted link 51 that receives a pin 52 projecting from a collar 53 fixed to the 50 shaft 40. It will therefore be seen that the shaft 40 is forcibly moved adjacent its limit of movement in either direction for effecting a positive clutch action between the clutch member 43 and either of clutch members 39. 55 In the operation of the apparatus, it being noted that the motor 36 constantly drives the motor shaft 37 in one direction and assuming that the piston 18 is in the end of the cylinder 12 adjacent the end wall 14 and 60 with the clutch member 43 engaged with a clutch member 39, cause reciprocation of the piston rod 28 to move the piston 18 away from the end wall 14, air is drawn into the cylinder 12 through the tensioned check valve 65 15 until the piston 18 reaches its limit of

movement toward the inner end of the cylinder 12 and at which time, the worm 44 and the worm wheel 45 effect shifting movement of the shaft 40 to engage the clutch member 43 with the other clutch member 39 whereupon the piston 18 will again move toward the end wall 14 of the cylinder 12 and during such movement, air confined within the cylinder 12 will be partially compressed and escapes by way of the check valve 19 into the intermediate cylinder 11. When the piston 18 again moves toward the cylinder 11, air in the latter cylinder is partially compressed and escapes by way of the check valve 31 into the compressor cylinder 13. When the piston 27 in the cylinder 13 moves toward the partition wall 20, air in the cylinder 13 is compressed and forced through the by path 23 into the chamber 24 and by way of the check valve 26 into the cylinder 13 between the piston 27 and end wall 25 thereof. The movement of the piston 27 from the partition 20 toward the end wall 25 again acts to compress air in the cylinder 13 and forces the same through lateral outlets 54 into a storage tank or other receptacle by way of check valves 55 set in pipes 56 with a single outlet pipe 57 leading to a tank.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

I claim:—

1. In an air compressor of the type described, a pair of aligned cylinders and an intermediate connecting housing, a partition separating an end and the intermediate housing, a reciprocating piston in each end cylinder with one piston separating the intermediate housing and an end cylinder, a check valve in the last named piston and partition, an air intake in the cylinder having the valved piston therein, an outlet in the other end cylinder, a rod connecting the pistons, and means for reciprocating the pistons.
2. In an air compressor of the character described, a pair of aligned cylinders and an intermediate connecting housing, one forming an air intake, the intermediate housing feeding air to the other cylinder which is a compressor cylinder, the compressor cylinder being of reduced diameter, pistons in the intake and compressor cylinders, a rod connecting the pistons and having a threaded portion and worm gear mechanism associated with the threaded portion of the rod for reciprocating the pistons and snap devices for reversing the operation of the worm gear mechanism.
3. In an air compressor of the character

described, a pair of aligned cylinders and an intermediate connecting housing, one forming an air intake, the intermediate housing feeding air to the other cylinder which is a compressor cylinder, the compressor cylinder being of reduced diameter, pistons in the intake and compressor cylinders, a rod connecting the pistons and having a threaded portion and worm gear mechanism associated with the threaded portion of the rod for reciprocating the pistons and snap devices for reversing the operation of the worm gear mechanism, valves controlling communication between the cylinders and intermediate housing and the compressor cylinder having an outlet to a storage tank.

In testimony whereof I affix my signature.

ARTHUR JOSEPH COURTOIS.
